UNITED STATES PATENT OFFICE.

H. HERMAN WESTINGHOUSE, OF PITTSBURG, PENNSYLVANIA, ASSIGNOR TO
THE WESTINGHOUSE MACHINE COMPANY, OF SAME PLACE.

STEAM-ENGINE.

SPECIFICATION forming part of Letters Patent No. 340,021, dated April 13, 1886.

Application filed January 13, 1886. Serial No. 188,426. (No model.)

To all whom it may concern:

Be it known that I, H. HERMAN WESTINGHOUSE, residing at Pittsburg, in the county of Allegheny and State of Pennsylvania, a citizen of the United States, have invented or discovered a certain new and useful Improvement in Steam-Engines, of which improvement the following is a specification.

In the accompanying drawings, which make part of this specification, Figure 1 is a horizontal central section through the cylinder and steam-chest, and a plan view of other members of a steam-engine embodying my invention; and Fig. 2, a vertical longitudinal central section through the steam-chest, with the governor and valve-connections in elevation.

The object of my invention is to provide a steam-engine in which the operative economy due to the utilization of steam expansively by compounding may be attained in a high degree, in conjunction with the advantages of structural simplicity and inexpensiveness; to which end my invention, generally stated, consists in the combination, in a compound engine, of a cylinder or cylinders having piston-spaces of differential areas, a single main or steam distribution valve adapted to supply boiler-steam to the smaller piston-space, to exhaust steam therefrom into the larger piston-space, and, finally, to exhaust it from the larger piston-space, and an automatic cut-off mechanism actuating said distribution-valve.

The improvement claimed is hereinafter more fully set forth.

Automatic cut-off engines in which the admission and exhaust of steam to and from the piston is effected by a single distribution-valve, and the speed regulated by a governor which varies the point of cut-off in correspondence with variations in load or pressure, or both, by changing the position of the eccentric which actuates the distribution-valve, are well known in the art of steam-engineering. The employment of mechanism of such character is general and approved, and in point of simplicity of construction, as well as in attaining substantially perfect regulation, it has been generally regarded as satisfactorily

answering the requirements of useful and practical service. So far, however, as economy of steam is concerned, it is considered by many to be defective to an extent such as to render its application undesirable in comparatively large engines, or in cases where the attainment of the best results derivable from a high grade of expansion is a leading or material object. The ground of such belief is, in brief, the fact that the valve cannot be made to perform its functions in a practically perfect manner for an earlier cut-off than about one half-stroke, as in such case there ensues an undue contraction of the area of steam admission, a premature opening of the exhaust, and an increased compression by reason of early exhaust closure, which so far reduces the power of the engine as to counterbalance the gain due to the higher grade of expansion. A further objection is the necessity of excessive clearance to admit of the compression commenced at early points in the stroke.

My invention is designed to enable the simplicity and effectiveness of automatic cut-off mechanism to be made available without the sacrifice of the economic advantages of the higher grades of expansion involved by its practical defects, as above indicated, when operated at early points of cut-off, and this object I attain by a novel combination of members, as hereinafter described, in which, while the limit of effective performance of its functions by the valve is not exceeded, as high a degree of expansion may be attained as is desirable or practicable.

As an exemplification of the practice of my invention, the drawings illustrate a single-cylinder double-acting compound engine of the trunk-piston class, having piston-spaces of different volumes, respectively, on opposite sides of its piston; but it will be obvious to those skilled in the art that my improvement is, without change of principle or essential operative members, equally applicable to compound engines of the ordinary type, in which the differential piston-spaces to be filled with boiler-steam and exhaust-steam, respectively, are located in two cylinders of unequal

volumes. The cylinder 1, which is closed at its ends by removable heads 2 3, is fixed upon a bed-plate, 4, which carries the bearings 5 of a crank-shaft, 6, having a pair of cranks, 7, connected by a crank-pin in the usual manner. The piston 8, which fits truly in the cylinder, is formed integral with or secured to a cylindrical trunk, 9, which projects centrally from one side of the piston, and passes freely through the cylinder-head 3 nearest the crank-shaft 6, leakage of steam being prevented by a properly-packed stuffing-box, 10, having a gland or packer, 11. A cross-head, 12, which is fitted to work between guides 13 on the bed-plate, is fixed upon the outer end of the trunk 9, and a pin, 14, passing through the central portion of the cross-head, is coupled by a connecting-rod, 15, to the pin of the cranks 7. It will be seen that the presence of the trunk 9 reduces the effective area of the adjacent side of the piston to the annular surface comprehended between its periphery and that of the piston, while the entire surface of the opposite side of the piston being subject to steam-pressure constitutes effective area. The maximum volume of the annular space 16 on the trunk side of the piston is correspondingly less than the maximum volume of the cylindrical space 17 on the opposite side, the ratio of difference between said areas and volumes resultant upon the relative diameters of the trunk and cylinder, as the same may be apportioned, determining the grade of expansion practicable in the cylinder, similarly to the difference of diameters of the cylinders in an ordinary two-cylinder compound engine. Steam is admitted to and exhausted from the cylinder-spaces 16 17 on opposite sides of the piston by a main or steam-distribution valve, 18, of the piston class, having pistons 19 20 at or near its ends, connected by an intermediate hollow or tubular body, said valve being fixed upon a stem, 21, and fitting truly in a cylindrical steam-chest, 22, cast upon or secured to the cylinder 1. A port or passage, 23, leads from the outer end of the cylinder-space 16 to the steam-chest, and a similar port, 24, leads from the outer end of the cylinder-space 17 to the steam-chest. Communication is established, in the traverse of the valve 18, between the ports 23 and 24, through the interior of the body of the valve, by a series of ports, 25 26, located in the end pistons, 20 and 19, respectively. Steam from the boiler is admitted to the steam-chest through a steam-supply opening or nozzle, 27, located therein between the ports 23 and 24, and, after performing its work in the cylinder, is exhausted from the chest through an exhaust opening or nozzle, 28, in the end thereof adjacent to the port 24. The distribution-valve 18 is actuated by an automatic cut-off mechanism, as presently to be described, and in its reciprocating movements within the chest 22 performs the functions of first admitting boiler-steam from the steam-

pipe and supply-nozzle 27 through the space around the body of the valve between its end pistons, 19 20, and through the port 23 to the smaller piston-space, 16, such steam acting upon the smaller piston-area on the side next the trunk, and effecting the left-hand stroke of the piston 8. By its ensuing movement to the left the valve next exhausts the steam from the smaller piston-space, 16, into the larger piston-space, 17, on the opposite side of the piston, by placing the cylinder-ports 23 and 24 in communication through the valve-ports 25 and 26 and the interior of the body of the valve, such exhaust-steam acting at correspondingly-reduced pressure on the larger piston-space, 17, upon the full area of the piston, and effecting the right-hand stroke thereof. The valve next moves to the right, thereby opening the port 23, to receive boiler steam for the succeeding left-hand stroke, and placing the port 24 in communication with the exhaust-opening 28, through which the low-pressure steam which has effected the right-hand stroke of the piston is exhausted to the atmosphere or to a condenser, as the case may be.

The automatic cut-off mechanism by which the distribution-valve is actuated may be of any suitable and preferred construction which embodies as essential elements a centrifugal governor or regulator fixed upon the crank-shaft of the engine, or upon a counter-shaft rotated thereby, and an eccentric mounted freely upon the shaft of the governor, and coupled to the governor, so as to be varied in position thereby transversely to the axis of the shaft, in accordance with the movement of the governor-weights under variations of pressure and load, or both. In the instance shown the eccentric 29, which is fitted freely on the crank-shaft by a slot inclosing the same, is pivoted by a pin, 30, to the supporting disk or carrier 31 of a centrifugal governor fixed upon the crank-shaft 6, and is coupled by a link, 32, to the centrifugally-acting governor-weights 33. The strap 34 of the eccentric is secured to one end of an eccentric-rod, 35, the opposite end of which is coupled to the valve-stem 21. The eccentric 29 being moved substantially transversely to the shaft by the inward and outward movements of the governor-weights, the effect of changes in its position induced thereby is to increase or diminish, as required, the length of traverse of the distribution-valve without varying the lead thereof, such changes in the traverse of the valve serving to maintain proper regulation by increasing or diminishing the supply of steam, and not changing to any material degree the adjusted grade of expansion at which the valve will normally perform its distribution function.

It will be obvious that where circumstances render such arrangement desirable the governor and eccentric may be mounted upon an independent or counter shaft, to which rota-

tion is imparted from the main or crank shaft, and, further, that as the governor and distribution-valve do not in and of themselves form part of my present invention, the construction 5 of said members may be varied materially from that herein shown without departing from the spirit of my invention.

The function of the automatic cut-off mechanism in the combination is simply to effect 10 the actuation of the distribution-valve and maintain uniform regulation of speed within the limits of a comparatively low grade of expansion—say not exceeding one half-stroke—and such mechanism, unless acting in combination 15 with means for utilizing steam at a higher grade of expansion, would, as before indicated, be insufficient and unsatisfactory for the attainment of the operative economy desired. The means provided for this purpose 20 consist of differential cylinder-spaces adapted to receive, respectively, boiler-steam and exhaust-steam, and these, whether controlled by one or more distribution-valves, would in turn be imperfect, unless when, as under my 25 invention, coacting with a valve-actuating and

speed-regulating mechanism of simple construction, which is substantially relieved from the duty of performing cut-off functions.

I claim herein as my invention—

The combination, in a compound engine, of 30 a cylinder or cylinders having piston-spaces of differential volumes, a main or steam-distribution valve adapted to effect successively the admission of boiler-steam to the smaller piston-space, the exhaust of steam therefrom into the larger piston-space, and the exhaust 35 from the larger piston-space, an eccentric mounted on the crank-shaft, with the capacity of movement transversely to the crank-line, and having its strap coupled to the stem of 40 the distribution-valve, and a governor fixed upon the crank-shaft and coupled to said eccentric, substantially as set forth.

In testimony whereof I have hereunto set my hand.

H. HERMAN WESTINGHOUSE.
